UNITED STATES PATENT OFFICE

118,491

DESIGN FOR A COMBINATION WALLET AND COSMETIC CONTAINER

Rita Bach, New York, N. Y.

Application November 24, 1939, Serial No. 88,445

Term of patent 7 years

To all whom it may concern:

Be it known that I, Rita Bach, a citizen of the United States and a resident of the city of New York, in the county of New York and State of New York, have invented a new, original, and ornamental Design for a Combination Wallet and Cosmetic Container, of which the following is a specification, reference being had to the accompanying drawing, forming a part thereof.

Fig. 1 is a front elevational view of a combination wallet and cosmetic container showing my new design in closed position; and

Fig. 2 is a perspective view thereof in partly open position.

The rear of the combination wallet and cosmetic container is substantially plain.

I claim:

The ornamental design for a combination wallet and cosmetic container, substantially as shown and described.

RITA BACH.
